UNITED STATES PATENT OFFICE

RICHARD E. KRUEGER, OF MADISON, WISCONSIN, ASSIGNOR TO GENERAL LABORATORIES, INC., OF MADISON, WISCONSIN, A CORPORATION OF DELAWARE

FLUID INJECTOR

Application filed September 22, 1930. Serial No. 483,482.

This invention relates to fluid injectors, and is in the nature of an improvement on prior application No. 410,624, filed November 29, 1929.

Generally stated, the object of the invention is to provide a novel and improved construction of Venturi tube for use in an injector of this kind, whereby the throat of said tube can be easily removed without disturbing the other parts, for cleaning or other purposes.

It is also an object to provide certain details and features of construction tending to increase the general efficiency of a Venturi tube for this particular purpose.

To the foregoing and other useful ends, the invention consists in the matters herein-after set forth and claimed, and shown in the accompanying drawings, in which,—

Fig. 1 is a side elevation of a fluid injector embodying the principles of the invention, showing the Venturi tube more or less in longitudinal section.

Fig. 2 is a vertical section on line 2—2 in Fig. 1 of the drawings.

Fig. 3 is a detail section on line 3—3 in Fig. 2 of the drawings.

Fig. 4 is a detail section on line 4—4 in Fig. 1 of the drawings.

As thus illustrated, the invention comprises a front section 1, which is preferably concave inside and convex outside, being substantially one-half of a spherical body, the other half being a similarly shaped rear section or cover 2, the two sections being clamped together, with a rubber diaphragm 3 between them, by the clamping bolts 4 that extend through the meeting flanges of the two sections. The section 1 has a top inlet 5 for the liquid which is to be ejected into the water, a suitable closure 6 being provided to seal the top of this opening or inlet, after the substantially spherical reservoir or storage chamber 7 is filled or charged. This chamber 45 has a bottom outlet 8 in the section 1, and the section 2 has a top water inlet 9, and a bottom water outlet 10, or valve drain, whereby the water can be drained out after the disinfectant or other liquid has been discharged through the outlet 8 into the water or other

liquid. A Venturi tube 11 disposed horizontally and secured laterally against the seat 12 formed on the side of the section 1 by screws 13 inserted through the flat bracket portion 14 of the said Venturi tube. A valve plug 15 is inserted through the Venturi tube, vertically, having a lateral inlet 16 communicating with the throat 17 of the Venturi tube, which inlet 16 communicates also with the outlet 8 previously mentioned. A tube 18 is screwed into the Venturi tube, as shown in Fig. 2 of the drawings, and projects a distance into the passage 8 previously mentioned, being of smaller diameter than said passage.

The water enters the Venturi tube through the valve 19 at the left in Fig. 1, and escapes from the Venturi tube through the similar valve 19 at the right in Fig. 1, whereby the water has a straight course through the injecting device. The Venturi tube 11 has an outlet 20 at a point some distance in advance of the opening 16, previously mentioned, and this outlet 20 is connected by a pipe 21 with the needle valve device 22, which latter is in turn connected with the inlet passage 9, previously mentioned, by the connection 23, as shown in Fig. 4 of the drawings. In this way, the water pressure from the outlet 20 through the connections to the inlet 9 can be regulated to suit the requirements. In a Venturi tube, such as shown, the water pressure will be greater at 20 than at 16, and the differential between these two points is sufficient to cause the water to pass upwardly through the pipe 21 and into the inlet 9, and from the latter into the space between the section 2 and the diaphragm 3, previously mentioned. This pressure continuing, the contents of the chamber 7, which is the space between the diaphragm 3 and the section 1, will be gradually forced out, through the outlet 8 and through the passage 16 and the tube 18, into the stream of water passing through the throat 17 of the Venturi tube, whereby water escaping through the valve 19 at the right will contain the disinfectant or other liquid. There are many liquid preparations, of course, for treating or purifying water, such as the water used for domestic purposes, but such liquid prepara-

tions need not be here described, as the invention is not limited to any particular liquid or compound for this purpose.

After the chamber 7 has been discharged of its contents, the water can then be shut off with the valve 19 at the left and the water removed from behind the diaphragm 3 by opening the drain valve 10. When the water is discharged from the injector, in a manner 10 that will be readily understood, and the apparatus is again filled or charged, through the top inlet 5, the diaphragm 3 will then return to the position shown in Figs. 2 and 3 of the drawings.

15 A small valve 24 can be used at the point shown, and this valve can be opened to relieve the apparatus of air during the filling operation, and to test the apparatus, the glass sight tube 25 can be employed in the water connection plug to valve 22, so that it can be observed whether the water is flowing downwardly in this connection, in the required manner, after the valves 19 and 22 are opened.

20 The construction shown and described is simple and comparatively inexpensive and facilitates opening the apparatus for inspection or repairs. For example, the back section 2 can be removed by simply removing the nuts from the bolts 4, thus permitting the removal of the diaphragm 3, as well, without disturbing or breaking any of the pipe connections. Moreover, by providing the tapered valve plug 15, the throat 17 and 25 a portion of the tube, practically, are removed, and can be easily cleaned by dipping in an acid solution. It has been found that when the water and liquid mix at the entrance of the throat 17 of the Venturi tube, 30 a precipitation takes place which clogs the tube at the point of contact between the liquid and the water. Thus the portion of the tube that clogs can be removed and cleaned. And, in addition, another advantage of this 35 construction is that the plug 15 can be used as a valve to stop dosage or injection of the liquid into the water when such is necessary or desirable; and, furthermore, this valve may also be used to advantage during the 40 filling of the container.

The tube 18 is found to be of advantage in the injection of the liquid into the water, and the flat seat 12 is also of advantage in holding the Venturi tube detachably in place, 45 as hereinafter explained.

The diaphragm 3 is preferably of rubber, or other flexible material, and is preferably molded to normally assume the shape shown in the drawings, whereby this diaphragm 50 normally conforms to the inside contour of the section 2 of the container. In this way the diaphragm has no tension or resiliency that would tend to force the liquid into the stream of water, so that the water pressure itself is 55 alone responsible for the injection of the

liquid into the water. Furthermore, as the diaphragm is practically hat-shaped, it can turn wrong side out, so to speak, and can be made to conform to the interior of the section 1 of the container when the liquid is entirely discharged into the water, and in such position the diaphragm will remain until forced back into normal position by a refilling or recharging of the liquid reservoir through the inlet 5, as previously described. The diaphragm 3, or other suitable pressure responsive means or element, forms a structural separation between one liquid and the other liquid, whereby water cannot pass through the connections 20, 21, 22 and 25 into one compartment, and from the latter into the other compartment, there being a physical or structural separation between the water pressure compartment and the solution compartment, whereby entrapment of air in either or both compartments is unnecessary, and is entirely avoided.

The tube 18 has three functions: To center the Venturi tube accurately in place during assembling; to hold the gasket in place on seat 12 during assembling; and to reduce the dilution of the charge under minor fluctuations of pressure, due to small diameter of comparatively great length of tube.

What I claim as my invention is:

1. In a liquid injector, the combination of instrumentalities forming a passage for the liquid that is to receive the injection therein of another liquid, having provisions to provide a differential pressure as between two successive points in said passage, and pressure operated means forming a structural separation between one liquid and the other and responsive to and operable by the higher pressure at one point to force said other liquid into said passage at said other point, said instrumentalities and provisions comprising a Venturi tube having a removable throat portion provided with a lateral inlet at the point of greatest restriction of said tube, said removable throat portion comprising a tapered plug having a straight bore forming said restriction, and having said lateral inlet located at the middle of said bore for the liquid to be injected into the other liquid.

2. In a liquid injector, the combination of instrumentalities forming a passage for the liquid that is to receive the injection therein of another liquid, having provisions to provide a differential pressure as between two successive points in said passage, and pressure operated means forming a structural separation between one liquid and the other and responsive to and operable by the higher pressure at one point to force said other liquid into said passage at said other point, said instrumentalities and provisions comprising a Venturi tube having a removable throat portion provided with a lateral inlet at the point of greatest restriction of said tube, said

throat portion having said lateral inlet for the liquid to be injected into the other liquid, said inlet comprising a tube projecting from the inner side of the Venturi tube, and said injector having a bore enclosing said inlet tube, the bore being of greater diameter than the inlet tube.

3. In apparatus for handling liquids, a Venturi tube provided with a removable throat portion, forming the greatest restriction of the tube, the opposite end portions of said tube having longitudinal passages tapered to the diameter of the opposite ends of said restriction, said removable throat portion comprising a rotary valve plug which is removable axially from the Venturi tube.

4. In a liquid injector, the combination of instrumentalities forming a passage for the liquid that is to receive the injection therein of another liquid, having provisions to provide a differential pressure as between two successive points in said passage, and pressure operated means forming a structural separation between one liquid and the other and responsive to and operable by the higher pressure at one point to force said other liquid into said passage at said other point, said instrumentalities and provisions comprising a Venturi tube having a removable throat portion, said throat portion having a lateral inlet for the liquid to be injected into the other liquid, said inlet comprising a tube projecting from the inner side of the Venturi tube, and said injector having a bore enclosing said inlet tube, the bore being of greater diameter than the inlet tube.

Specification signed this 18 day of September, 1930.

RICHARD E. KRUEGER.
